UNITED STATES PATENT OFFICE

JESS CLAIR KELLY, OF CAMBRIDGE, OHIO

DESIGN FOR A GOBLET OR SIMILAR ARTICLE

Application filed September 21, 1931. Serial No. 41,175. Term of patent 3½ years.

To all whom it may concern:

Be it known that I, JESS CLAIR KELLY, a citizen of the United States of America and resident of Cambridge, county of Guernsey, and State of Ohio, have invented a new, original, and ornamental Design for a Goblet or Similar Article, of which the following is a specification, reference being had to the accompanying drawings, in which—

Figure 1 is a side elevation of a goblet or similar article showing my new design; and—

Figures 2 and 3 are sections taken, respectively, on lines 2—2 and 3—3, Fig. 1.

The invention resides in the stem shown as associated with a bowl and base of the general character disclosed.

I claim:—

The ornamental design for a goblet or similar article substantially as shown and described.

JESS CLAIR KELLY.
